John A. Diederichs,

ATTORNEY.

UNITED STATES PATENT OFFICE.

JOHN CROSSY, OF PHILADELPHIA, PENNSYLVANIA.

MEANS FOR OPERATING STAGE-SCENERY.

SPECIFICATION forming part of Letters Patent No. 248,028, dated October 11, 1881.

Application filed August 10, 1881. (No model.)

To all whom it may concern:

Be it known that I, JOHN CROSSY, a citizen of the United States, residing at Philadelphia, in the county of Philadelphia, State of Pennsylvania, have invented a new and useful Improvement in the Means and Method of Operating Stage Scenery and Properties, which improvement is fully set forth in the following specification and accompanying drawings, in

10 which—

Figure 1 is a front view of a stage embodying my invention. Fig. 2 is a vertical section of a portion thereof. Fig. 3 is a top view of a portion. Fig. 4 is a plan view, reduced, of the

15 stage.

Similar letters of reference indicate corresponding parts in the several figures.

My invention consists of scene-supports secured to rotary platforms on the floor of the 20 stage, so that scenes can be quickly changed or transformed, whereby while one set is in service another may be prepared and set ready to be swung around for use.

It also consists of grooves or supports and 25 braces for the wings or box scenes, flats, &c., which may be readily set out and folded, as desired.

It also consists of means for simultaneously 30 operating the grooves or supports.

35 It also consists of certain details of construction, as will be hereinafter stated.

Referring to the drawings, A represents a stage for theatrical and other performances, and B the floor thereof.

35 C represents rotary platforms or turn-tables, which are properly mounted on foundations beneath the floor B and set level, or nearly so, as desired, with the floor B. In the present case there are four platforms, C, and they are 40 geared together so that they may be simultaneously operated, the gearing being suitable spur-wheels connected to the platforms and meshing with each other, or band-wheels and belts, or other devices, which are operated by 45 means of a crank-shaft, pulley, or other device properly applied.

Rising from each platform C are uprights D, which support a head, E, on which is fitted a horizontally-sliding bar, F, and to the sides of 50 the head are pivoted the grooves or supports G, which are connected to the bar F so as to

be folded against or opened out from said head E. For this purpose the bar F may be formed with teeth or racks *a*, and the pivots of the supports G with pinions or segments *b*, with which the racks of the bar F mesh or engage, so that the movement of the bar in one direction opens the supports G, so that flats, wings, &c., may be fitted to said supports G, as in the left-hand side of Fig. 1, and the movement of 60 the bar in the other direction closes and folds said supports G, as shown in the right-hand side of Fig. 1. The movement of the supports G may, however, be accomplished by pivoting them to the head E, and pivoting their inner 65 ends to the bar F, so that the in and out movements or folding and unfolding of the supports may be accomplished by operating the slide or bar F.

Motion may be imparted to the bar by means 70 of a lever, F', which is pivoted to the head E and fitted in a notch or slot in the bar, or by providing the bar with a rack or teeth, with which engages a pinion provided with a crank-handle, F', as seen in Fig. 2.

To the head E is pivoted a series of braces, H, one for each support G, and formed of sections hinged or pivoted to each other, so as to be set at various angles relatively to the support G and the connected flat, wing, &c. In 80 order to hold the braces when adjusted they are provided with screws or bolts *d*, which enter the floor of the stage or keepers thereon, and so steady and sustain the braces.

When a scene is in service the several members of another scene and properties may be prepared and set behind the first-named scene, by which they are concealed. At the proper time the platforms C are rotated, whereby the old scene disappears and the new one is presented, provision thus being made for transformations in a convenient and rapid manner.

Suitably mounted on shafting, operated by the gearing of the platforms, are windlasses, drums, or pulleys J, around which are passed cords K, which are connected to the borders, drop-curtain, &c., mounted overhead of the stage, as at L, whereby during the operation of the platform and consequent shifting of the scenes the borders, &c., are shifted in harmony 95 with the wings, flats, &c.

If desired, the braces H may be set to sup-

port or steady backgrounds, drops, and other parts extending from side to side of the stage.

Having thus described my invention, what I claim as new, and desire to secure by Letters 5 Patent, is—

1. A rotary platform provided with a scene-supporting device, substantially as and for the purpose set forth.
2. Two or more rotary platforms provided 10 with scene-supporting devices adapted to operate in concert, substantially as and for the purpose set forth.
3. The braces H, in combination with the uprights D, said braces being formed of parts 15 pivoted to each other and to said uprights, substantially as and for the purpose set forth.
4. The hinged groove or support G, in com-

bination with a connected slide or bar and an operating-handle, substantially as and for the purpose set forth.

5. The series of grooves or supports G and an operating-bar, F, common thereto, whereby the supports may be simultaneously folded and unfolded, substantially as and for the purpose set forth.

6. The scene-supporting rotary platforms provided with gearing, in combination with pulleys geared therewith, and the cords of the borders or drops, substantially as and for the purpose set forth.

JOHN CROSSY.
